[57] CLAIM

The ornamental design for a compact disc jukebox, as shown and described.

DESCRIPTION

FIG. 1 is a front and left side perspective view of a compact disc jukebox showing my new design;
FIG. 2 is a front elevational view thereof;
FIG. 3 is a rear elevational view thereof;
FIG. 4 is a top plan view thereof;
FIG. 5 is a bottom view thereof; and,
FIG. 6 is a right side elevational view thereof, the left side being a mirror image.
The partially shown images behind the transparent panel in FIGS. 1 and 2 are to show environment only and form no part of the claimed design.

Fig. 1.
